UNITED STATES PATENT OFFICE

148,934

DESIGN FOR A SADDLE

Lou Kosloff, Hollywood, Calif.

Application August 28, 1946, Serial No. 132,920

Term of patent 7 years

(Cl. D38—7)

To all whom it may concern:

Be it known that I, Lou Kosloff, a citizen of the United States, residing at Hollywood, in the county of Los Angeles and State of California, have invented a new, original, and ornamental Design for a Saddle, of which the following is a specification, reference being had to the accompanying drawing, forming part thereof.

In the drawing:

Fig. 1 is a side elevational view of a saddle showing my new design;

I claim:

The ornamental design for a saddle, as shown.
LOU KOSLOFF.
